(57) **CLAIM**

We claim the ornamental design for a read device for optically reading information, as shown and described.

DESCRIPTION

FIG. 1 is a perspective view of a read device for optically reading information, showing a new design;

FIG. 2 is a front view of the read device shown in FIG. 1; FIG. 3 is a rear view of the read device shown in FIG. 1; FIG. 4 is a right side view of the read device shown in FIG. 1;

FIG. 5 is a left side view of the read device shown in FIG. 1;

FIG. 6 is a top view of the read device shown in FIG. 1; and, FIG. 7 is a bottom view of the read device shown in FIG. 1. The broken lines and unshaded portions contained within broken lines depict exemplary components of the read device that are being shown for illustrative purposes only and that form no part of the claimed design.
